Max S. Finley, INVENTOR.

BY
Geo. P. Kimmel
ATTORNEY

UNITED STATES PATENT OFFICE.

MAX S. FINLEY, OF INDIANAPOLIS, INDIANA.

RADIO TELEPHONE RECEIVER.

Application filed July 10, 1922. Serial No. 573,967.

To all whom it may concern:

Be it known that I, MAX S. FINLEY, a citizen of the United States, residing at Indianapolis, in the county of Marion and State of Indiana, have invented certain new and useful Improvements in Radio Telephone Receivers, of which the following is a specification.

This invention has reference to radio phone receivers and its object is to reduce the cost of such a receiver to an extreme minimum so that the instrument may be sold at an extremely low cost and yet provide a workable device.

On account of the large demand for radio instruments and the high cost of such instruments, especially with respect to receivers, a demand has grown up for great cheapness of production, and by the present invention, the demand is met at a cost bringing the total expense of a radio receiving set of workable efficiency to an extremely low price.

The result is that those who desire to listen in may install their own radio sets at a cost so small that any one may invest therein and still obtain results all out of proportion to the cost thereof.

The cost of the receiver is so small as to make it feasible to give away such receivers as advertising devices, while still obtaining good workable results.

The invention will be best understood from a consideration of the following detailed description taken in connection with the accompanying drawing, forming part of this specification, with the understanding that the invention is not confined to any strict conformity to the showing of the drawings, but may be changed and modified so long as such changes and modifications come within the scope of the appended claim.

In the drawings:—

Figure 1 is a perspective view of a radio telephone receiver.

Fig. 2 is a longitudinal central section therethrough.

Fig. 3 is a section on the line 3—3 of Fig. 2.

Referring to the drawings, there is shown a cylinder 1 with caps 2, 3, at opposite ends.

Within the cylinder 1 there is another cylinder 4, the cylinder 1 being in effect a simple sheet of paper for containing advertising matter while the cylinder 4 is thick and stout

enough to effectively resist handling and also to provide a thickness sufficient for insulating purposes, which insulating effect may be increased by coating the interior of the cylinder 4 with shellac or some other suitable insulating material.

The cap 2 is provided with a central opening 5 of appropriate size to permit the escape of sound waves, while the cap 3 is provided with an opening 6 to permit the passage of a twisted conductor 7 which latter is held in place against the cap 3 by a paster 8 or in other suitable ways.

Within the cylinder or body portion 4 there is lodged a permanent horse shoe magnet 9 which, because of cheapness, may be of the familiar toy type and held in any suitable manner within the cylinder 4, as for instance, by tightness of fit, thus doing away with any additional expense in installation since such tightness of installation will resist displacement due to handling.

Surrounding the polar ends 10 of the electromagnet 9 is a sleeve 11, which may be formed of paper, shellacked or otherwise stiffened, and on the sleeve 11 is wound a coil 12 of insulated wire of sufficient length and gage to produce a coil of high resistance, say of one thousand or two thousand ohms, the wire being preferably of number 44 gage.

The coil 12 is provided with terminal extensions 13 carried through insulating tubes 14 within the main tube 4 and there coupled to heavier conductors 15 forming part of the conductor 7.

Within the zone of influence of the magnet 10 is a diaphragm 16 of magnetic material such as a sheet of soft iron such as is used in telephone receivers. The wires of the conductor 7 terminate in clips 15 by means of which the radio receiver may be electrically connected to an aerial or to ground as the case may be.

Despite the low cost of the telephone receiver for radio purposes, the results are remarkably good and the invention permits any one desiring to avail himself of the greatly extended broadcasting of radio messages to do so at but a small cost practically negligible in amount.

What is claimed is:—

In a telephone receiver a double walled cylindrical casing having its walls arranged in spaced relation, an apertured head for each end of said casing formed with an in-

wardly extending annular flange inserted between the said walls, a horseshoe magnet secured within said casing, a coil surrounding the poles of said magnet and having the terminal wires thereof passing out through the aperture in one of said heads, a diaphragm secured to and extending across the

aperture in the other head, and means for connecting said terminal wires with a receiving set.

In testimony whereof, I affix my signature hereto.

MAX S. FINLEY.
